EDWARD J. FRANKLIN, OF SALT LAKE CITY, UTAH

SELF-ADJUSTING SEAL FOR JOINTS OF FURNACES

Application filed January 28, 1930. Serial No. 424,124.

This invention relates to means for sealing the joints of furnaces and the main object of the invention is to provide means for sealing or closing the joints between the parts of the furnace wall which are subject to relative displacement by expansion and contraction due to temperature changes, the invention being particularly directed to the provision of sealing means which will be self-adjusting 5 so as to maintain tight closure notwithstanding such temperature changes.

A further object of the invention is to provide an improved, serviceable, flexible, readily applied, refractory sealing means to those parts within or without a furnace structure, between which parts there exists a relative movement due to the expansion or contraction of those or adjacent parts, when influenced by the heating or cooling of such parts 10 when the furnace is being operated.

In the usual types of boiler or other furnaces, there ordinarily exist several points at which some metal part of the boiler structure or water wall system is located adjacent to some portion of the materials composing the walls or other closure, surrounding the furnace. Furthermore, there is usually more or less relative movement existing between these parts, due to the inevitable expansion 15 of the several members which comprise the complete boiler and setting structure.

The usual practice in boiler setting construction is to so proportion the dimensional relationship between the several parts that there is a void or free space provided between the parts between which relative expansion is expected. This void, or free space, is customarily filled or packed with a quantity of 20 some fireproof, resilient material, as for example, asbestos fiber, such material being tamped into place to the density required to maintain a tight and slightly resilient or yielding seal between the parts in question. 25 This method of providing a resilient seal is not always successful in that the resilient material has a tendency to work out of the space in which it is placed, due to the continual motion of the boundaries of the confining space, and also to the fact that the ma-

terial collects dust, hardens in time and therefore becomes useless.

In my invention, I propose to substitute a flexible, refractory sealing arrangement for the more usual packed joints just above described, such a refractory seal arrangement to be so constructed that relative motion between the adjacent parts may take place in any direction, without affecting the efficacy of the sealing arrangement. The manner in which this object is accomplished may more readily be seen by reference to the accompanying drawings, and to the detailed description applying to each of the same.

The accompanying drawings illustrate embodiments of my invention and referring thereto:

Fig. 1 is a front elevation of the sealing means.

Fig. 2 is a section on line 2-2 in Fig. 1. 70

Fig. 3 is a section on line 3-3 in Fig. 2.

Fig. 4 is a section on line 4-4 in Fig. 2.

Fig. 5 is a vertical section of a portion of a furnace bottom showing the application 75 of my invention in connection therewith.

Fig. 6 is a vertical section of a furnace boiler showing the application of my invention to the various joints thereof.

Fig. 7 is a section on line 7-7 in Fig. 6.

Fig. 8 is a vertical section showing the application of my invention in connection 80 with the seals at the upper and lower ends of a bent water tube wall.

Fig. 9 is a detail view showing the application of my invention to the mud drum. 85

Referring to Figs. 1 to 4, the seal is composed of a plurality of members 1 mounted end to end on a suitable support and cooperating with one another and with a supporting means to form a substantially gas tight seal while permitting self-adjustment to compensate for changes in temperature. Each member 1 may be formed as a wing plate of suitable refractory metal or material adapted to withstand the temperatures existing at that part of the furnace and resting by hinged connection on supporting or base members 2 which are mounted on a portion 3 of the furnace wall. The supporting members 2 are also preferably formed of a 90 95 100

series of sections of suitable refractory metal or material and the members 1 and 2 are connected by a hinged joint permitting rocking movement of the member 1 on the member 2. 5 For this purpose each member 2 may be provided with an upwardly extending flange or ridge 4 which extends the full length of the base 2 and has a rounded upper edge or bearing 5 on which rests a groove or concave 10 bearing 6 formed on the lower end of the adjacent member 1, the bearings 6 and 5 fitting one another so as to provide for rocking movement of the member 1 in a vertical plane. At its upper end each wing plate or member 1 15 rests against a portion 9 of the furnace wall or boiler, the parts being so positioned that the wing plates or members 1 are supported in sloping position and the center of gravity of each member 1 is between the bearing 5 20 and the wall portion 9 and the effect of gravity is such as to cause the seal member 1 to rest against the wall portion 9 and make a substantially gas tight connection therewith.

The members 2 preferably interlock with 25 one another by means of off-sets or projections 10 engaging recesses 11 in the adjacent members so as to more effectively close or seal the joint between adjacent members.

The seal members 1 also overlap one another as shown in Fig. 4 each member 1 being 30 provided with a flange 13 at one end extending over and in contact with a shoulder or rabbett 14 on the adjacent member 1 so as to form a substantially gas tight closure at 35 the joints between adjacent members.

An important application of my invention is in connection with means at the bottom of the boiler furnace for controlling the admission of air to the combustion chamber and 40 permitting discharge of ash therefrom, such a construction being desirable where coal dust is used as a fuel. Such a construction is shown in Fig. 5, the members 1 in that case being mounted by hinged connection 6, 5 on a supporting member 2 at each side of a bottom element for the furnace, said bottom element also comprising a central member 15 supporting a refractory furnace bottom element 16 mounted on supporting means comprising side walls 17 each side wall having 50 vertical flanges 9 against which rest the corresponding seal members 1, the seal members 55 rocking on the hinge bearing 5 and sliding on the vertical means 9 so as to adjust themselves to changes in relative position of the parts 2 and 17 due to temperature changes in the furnace.

In some cases it is desirable to provide the bearing member 9 against which the sloping 60 wing plate rests, with a ledge or shoulder as indicated at 9' in Fig. 5 so as to shed or deflect ashes from the joint between the members 1 and 9. This is, however, not necessary when the slope of the wing plate is steeper 65 than the angle of repose of the ash.

My improved seal is applicable generally in connection with any of the joints of a boiler furnace where displacement or distortion due to temperature changes is liable to take place. For example, as shown in Figs. 6 and 7, the sealing means can be applied as shown at 1a in connection with the furnace bottom similarly to the construction shown in Fig. 5 and may also be applied as shown at 1b at the junction between the furnace bottom 70 and the side wall of the furnace, the construction in that case being the same as shown in Figs. 1 to 4. Similarly, the seal may be applied as shown at 1c, 1d and 1e at each of the joints between portions of the furnace wall which are subject to displacement. The seal may also be applied as shown at 1f to a joint within the furnace chamber, for example, between deflector plates or walls 20 and 21 mounted on different parts 75 of the boiler construction and subject to relative displacement by reason of changes in temperature. The wing plate 1f may rest on supporting plates 2f which in this case may be clamped to certain of the boiler tubes by 80 suitable fastening means as shown. Said supporting plates may, however, be mounted on a bridge wall or other parts of the furnace.

In case the boiler is provided with water tube walls as shown at 23 in Figs. 6 and 7, said water tube walls may be made straight as shown, and the sealing means indicated at 1g may be provided between the headers 25 at the lower ends of the water tubes and the 100 side members 26 for the furnace bottom. By this means the expansion and contraction of the water tubes may be provided for without the use of the curved tubes which are generally considered necessary in order to provide for expansion and contraction of water tube walls. It will be understood that in the constructions above described the various members of the boiler including the headers and the water tubes are supported on suitable 105 supporting means at the top of the boiler or supported at the bottom or at the mid-height of the tubes in the usual manner and the various parts of the boiler construction so suspended or supported will be subject to displacement in the operation of the boiler by reason of changes in temperature, and the joints or connections between such parts of the boiler and adjacent wall members of the furnace will, therefore, be subject to relative displacement. By providing the above 110 described sealing means at such points or connections, the relative displacement referred to is provided for while maintaining a substantially gas tight closure and without 115 causing any strains or distortions of the parts of the boiler or of the water wall construction.

While my invention may be used with special advantage in connection with the provi- 120 125 130

sion for straight tube water walls, it may also be used to some advantage with water wall constructions comprising curved tubes since it reduces materially the strains which unavoidably occur with such constructions. Such a construction is illustrated in Fig. 8 in which the water wall tubes 28 which are bent at their upper and lower ends to connection with the headers 29 and 30 and are rigidly connected to side wall 31 by clamp means 32 and 33. A sealing member 1h, such as above described, is placed between the upper clamp member 32 and a flange member 35 on an upper wall portion 36 and a similar sealing member 1h is placed between the lower clamp member 33 and a support 38 on a lower wall member 37 so as to maintain substantially gas tight closure at the joints between said wall members. The water wall, comprising the tubes 28 and the backing member 31 therefor, may be supported at the upper header, or at the lower header, or at any intermediate point.

Fig. 9 illustrates the application of my invention to the several closures adjacent to the lower rear drum, commonly denoted as the "mud drum", of a vertical bent tube type boiler, such as the well known Stirling boiler. It is a well known and recognized fact that the actual position of this drum with respect to the boiler setting is continually changing, due to the influence of expansion of the several angularly disposed tubes attached thereto, when the boiler is in service. This relative motion has heretofore rendered very difficult the construction of satisfactory sealed, resilient joints between the drum and the adjacent furnace walls or other structures. In my invention, referring to Fig. 9, the mud drum 48 is suspended by a series of tubes 49 in the manner usually employed in boilers of this type. Upon the usual refractory bridge wall 50 is mounted the base piece 2m which supports the wing plate 1m. The wing plate rests at its upper edge against the bearing plate 9m which is attached to the shell of the drum 48, or it may bear directly upon the shell of said drum without the use of the bearing plate 9m.

At the rear of the mud drum, there is, in many instances, the need for a dust hopper to collect and dispose of the flue dust and other refuse, which otherwise would accumulate in the back passes of the boiler of the general type being considered. Ordinarily, some type of flexible or resilient junction must be made between the structure of such a dust hopper and the mud drum. Through the use of my invention, I provide such a flexible joint, as illustrated in Fig. 9. The dust hopper 52, which may be of any convenient or suitable shape is partially supported, for example, by the beam member 53, the balance of the supporting members being not shown. On the top of the beam member 53 is mount-

ed the base piece 2n carrying the wing plate 1n, which rests at its upper edge against the shell of the drum 48 either directly or through the medium of the bearing plate 9n attached to the shell of the drum.

I claim:

1. A sealing means for closing the joint between two adjacent members of a furnace construction comprising a supporting means mounted on one of said portions and provided with an upwardly extending flange, a plurality of sealing members hingedly mounted on said flange and extending upwardly therefrom and means on the other of said members of the furnace adapted to slidably engage the upper ends of said sealing members to seal the joint between said members while permitting relative movement thereof said supporting means being formed of a plurality of sections provided with overlapping means for sealing the joints between them.

2. Means for sealing the joint between two adjacent parts of a furnace construction comprising a supporting means in connection with one of said parts and having an upwardly extending flange rounded to form a bearing, a plurality of sealing members having concave bearing portions at their lower ends fitting on said rounded flange so as to permit hinge movement of said movable bearing members on said flange and means on the other said part of the boiler furnace construction adjacent said joint, adapted to engage the upper end portions of said sealing members to form a substantially gas tight connection therewith while permitting hinged movement of the sealing means.

3. A construction as set forth in claim 2 in which the flanged supporting means is formed in a plurality of sections and in which the movable sealing members and the sections of the flange supporting means are provided with overlapping portions for sealing the joints between them.

In testimony whereof I have hereunto subscribed my name this 9th day of January 1930.

EDWARD J. FRANKLIN.
